UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE

FLAT-SHEET-DELIVERY MECHANISM FOR PRINTING-PRESSES.

1,226,168.

Specification of Letters Patent.

Patented May 15, 1917.

Application filed September 21, 1915. Serial No. 51,788.

To all whom it may concern:

Be it known that I, HOWARD M. BARBER, a citizen of the United States, and resident of Stonington, in the county of New London 5 and State of Connecticut, have invented a new and useful Improvement in Flat-Sheet-Delivery Mechanism for Printing-PresSES, of which the following is a specification.

The object of this invention is to provide 10 novel means for preventing the sagging and falling ahead of the sheets in the delivery mechanism as the sheets are being delivered; said means including a yielding device traveling with the endless delivery carrier and arranged to engage the tail end of a sheet being delivered and press it against a stationary sheet support, which device as it rides off from the sheet support will deflect the tail end of the sheet downwardly 15 as its head end is released by the delivery carrier grippers.

Means may be provided for adjusting the said stationary sheet support and the said yielding device, one or both, to cause them 20 to act successfully on sheets of different lengths.

A practical embodiment of the invention is represented in the accompanying drawings, in which,

30 Figure 1 is a longitudinal vertical section through so much of a flat sheet delivery mechanism as embodies my invention.

Fig. 2 is an enlarged detail plan view.

Fig. 3 is a longitudinal vertical section 35 taken in the plane of the line A—A of Fig. 2, and

Fig. 4 is a detail horizontal section taken in the plane of the line B—B of Fig. 3.

In the embodiment shown in the accompanying drawings, the endless delivery carrier comprises the side chains 1, passing 40 around the sprocket wheels 2, 3, which endless delivery carrier is provided with one or more sets of grippers 4, 5, arranged to engage the head ends of the sheets as the sheets are fed through the rollers 6, 7, on to the guides 8 of the stationary sheet support, which guides extend part way along beneath the endless delivery carrier. There 45 may be any desired number of these guides 8, which guides are adjustably supported in brackets 9, 10, carried by cross-bars 11, 12, of the machine. These guides may be ad-

justed forwardly and rearwardly if desired, for sheets of different lengths; as for instance, by providing the brackets 9, 10, with clamp screws 13, 14. The sheet receiving table is denoted by 15, the front stops by 16, and the back joggers by 17. Downwardly inclined front sheet guides 18 are supported 55 from the arms 19, carried by the cross-bar 20, for directing the head ends of the sheets on to the table as they are released by the grippers 4, 5. A cam 21 is provided for controlling the operation of the grippers at the 60 receiving end of the delivery carrier and a cam 22 is provided for controlling the operation of the grippers at the delivery end of the carrier.

The yielding device for engaging the tail 70 ends of the sheets and pressing them against the stationary sheet guide and for deflecting the tail ends of the sheets downwardly as the head ends are released by the grippers and the tail ends leave the stationary support, is herein shown as comprising a plurality of spring-actuated rollers 23, one for each stationary sheet guide 8. Each of the rollers 23 is mounted on a stud axle 24 secured by a bolt 25 to the free end of a flat 75 spring arm 26, the other end of which arm is secured by a bolt 27 to a stud 28 screwed into a rigid arm 29 mounted on a cross-bar 30, the ends of which cross-bar 30 are secured to the side chains 1 of the endless delivery carrier by bolts 31.

The stud 28 may be turned in the arm 29 to secure the desired tension for the spring arm 26, and it is secured in such adjustment by a nut 32. The arm 29 is adjustable laterally along the cross-bar 30 to bring the roller 23 in alignment with its stationary sheet guide 8, and the arm is also rotatively adjustable on the bar 30, to adjust the device within a limited distance to sheets of 90 different lengths. A stud 33 serves to clamp the arm 29 in its desired lateral and rotative adjustments. If the rotative adjustment of the arm 29 is not sufficient, the bar 30 may be adjusted from link to link on the chains 95 of the endless delivery carrier. In the present instance I have shown two adjacent links 34 as being provided with lugs 35 for the attachment of the ends of the cross-bar 30.

In operation, the sheet as it comes from 105 the press is fed through the rollers 6, 7,

into position to be seized by the grippers 4, 5, of the endless delivery carrier. These grippers draw the sheet from the stationary sheet support. The yielding device hereinbefore described, is brought into engagement with the tail end of the sheet and presses the sheet against the stationary sheet support. As the grippers 4, 5, are opened to release the head end of the sheet, 5 the tail end of the sheet leaves the stationary sheet support and is deflected by the yielding device. The front sheet guide 18 serves to deflect the head end of the sheet and the sheet will thereby be deposited vertically on to the table 15, without any tendency of the sheet to sag or fall ahead.

It is obvious that the delivery carrier may be provided with any desired number of grippers and tail end sheet engaging devices, and it will be seen that the devices 20 may be adjusted together with the sheet support if so desired, to suit sheets of different lengths.

What I claim is:

25 1. A flat sheet delivery mechanism for printing presses including an endless delivery carrier, a sheet receiving table, a stationary sheet support, and means on the carrier coacting with said support for preventing the sagging and falling ahead of the sheet as it is being delivered onto the sheet receiving table.

30 2. A flat sheet delivery mechanism for printing presses including an endless delivery carrier, a stationary sheet support, and adjustable means on the carrier coacting with said support for preventing the sagging and falling ahead of the sheet as it is being delivered.

35 40 3. A flat sheet delivery mechanism for printing presses including an endless delivery carrier, a stationary sheet support, and yielding means on the carrier coacting with said support for preventing the sagging and falling ahead of the sheet as it is being delivered.

45 4. A flat sheet delivery mechanism for printing presses including an endless delivery carrier, a stationary sheet support, and adjustable yielding means on the carrier coacting with said support for preventing the sagging and falling ahead of the sheet as it is being delivered.

50 5. A flat sheet delivery mechanism for printing presses including an endless delivery carrier arranged to travel in partly circular and partly linear paths and having grippers for engaging the head end of the sheet and means on the carrier for deflecting the tail end of the sheet as its head end is released by said grippers.

55 6. A flat sheet delivery mechanism for printing presses including an endless delivery carrier having grippers for engaging the head end of the sheet, and adjustable means

on the carrier for deflecting the tail end of the sheet as its head end is released by said grippers.

7. A flat sheet delivery mechanism for printing presses including an endless delivery carrier arranged to travel in partly circular and partly linear paths and having grippers for engaging the head end of the sheet, and yielding means on the carrier for deflecting the tail end of the sheet as its head end is released by said grippers. 70

8. A flat sheet delivery mechanism for printing presses including an endless delivery carrier having grippers for engaging the head end of the sheet, and adjustable yielding means on the carrier for deflecting the tail end of the sheet as its head end is released by said grippers. 80

9. A flat sheet delivery mechanism for printing presses including an endless delivery carrier having grippers for engaging the head end of the sheet, a stationary sheet support and means on the carrier for engaging the tail end of the sheet as it is drawn along the stationary support and for deflecting the tail end of the sheet as it leaves said support and as its head end is released by said grippers. 85

10. A flat sheet delivery mechanism for printing presses including an endless delivery carrier having grippers for engaging the head end of the sheet, a stationary sheet support, and adjustable means on the carrier for engaging the tail end of the sheet as it is drawn along the stationary support and for deflecting the tail end of the sheet as it leaves said support and as its head end is released by said grippers. 95

11. A flat sheet delivery mechanism for printing presses including an endless delivery carrier having grippers for engaging the head end of the sheet, a stationary sheet support, and yielding means on the carrier for engaging the tail end of the sheet as it is drawn along the stationary support and for deflecting the tail end of the sheet as it leaves said support and as its head end is released by said grippers. 105

12. A flat sheet delivery mechanism for printing presses including an endless delivery carrier having grippers for engaging the head end of the sheet, a stationary sheet support, and adjustable yielding means on the carrier for engaging the tail end of the sheet as it is drawn along the stationary support and for deflecting the tail end of the sheet as it leaves said support and as its head end is released by said grippers. 115

13. A flat sheet delivery mechanism for printing presses including an endless delivery carrier, a stationary sheet support including a guide over which the sheet is drawn by said carrier and a yielding device on the carrier including a spring-actuated roller for pressing the tail end of the sheet 120

130

against said guide and for deflecting the tail end of the sheet after it leaves said guide to prevent the sagging and falling ahead of the sheet as it is being delivered.

- 5 14. A flat sheet delivery mechanism for printing presses including an endless delivery carrier, a stationary sheet support including a guide over which the sheet is drawn by said carrier and a yielding device 70
16 on the carrier including a spring-actuated roller for pressing the tail end of the sheet against said guide and for deflecting the tail end of the sheet after it leaves said guide to prevent the sagging and falling ahead of 75
15 the sheet as it is being delivered, and means for adjusting the position of the yielding device on the carrier for sheets of different lengths.

15. A flat sheet delivery mechanism for 20 printing presses including an endless delivery carrier, a stationary sheet support including a guide over which the sheet is drawn by said carrier and a yielding device on the carrier including a spring-actuated 80
25 roller for pressing the tail end of the sheet against said guide and for deflecting the tail end of the sheet after it leaves said guide to prevent the sagging and falling ahead of the sheet as it is being delivered, and means 85
30 for adjusting the stationary sheet support for sheets of different lengths.

16. A flat sheet delivery mechanism for printing presses including an endless delivery carrier, a stationary sheet support including a guide over which the sheet is drawn by said carrier and a yielding device on the carrier including a spring-actuated 90
35 roller for pressing the tail end of the sheet against said guide and for deflecting the tail end of the sheet after it leaves said guide to prevent the sagging and falling ahead of the sheet as it is being delivered, and means 95
40 for adjusting both the yielding device and the stationary sheet support for sheets of different lengths.

- 45 17. A flat sheet delivery mechanism for printing presses including an endless delivery carrier, a stationary sheet support, and means on the carrier coacting with said support and sheet for preventing the sagging and falling ahead of the sheet as it is being delivered, said means including a cross-bar 100
50 secured to the carrier, an arm mounted on said cross-bar, a spring arm secured to said 105
55 cross-bar arm and a roller carried by said spring arm.

18. A flat sheet delivery mechanism for printing presses including an endless delivery carrier, a stationary sheet support, and means on the carrier coacting with said support and sheet for preventing the sagging and falling ahead of the sheet as it is being delivered, said means including a cross-bar 110
60 secured to the carrier and adjustable along the same, an arm mounted on said 115
65 cross-bar arm and a roller carried by said spring- 120
70

cross-bar, a spring arm secured to said cross-bar arm and a roller carried by said spring arm.

19. A flat sheet delivery mechanism for printing presses including an endless delivery carrier, a stationary sheet support, and means on the carrier coacting with said support and sheet for preventing the sagging and falling ahead of the sheet as it is being delivered, said means including a 75
70 cross-bar secured to the carrier, an arm mounted on said cross-bar and adjustable thereon, a spring arm secured to said cross-bar arm and a roller carried by said spring arm.

80 20. A flat sheet delivery mechanism for printing presses including an endless delivery carrier, a stationary sheet support, and means on the carrier coacting with said support and sheet for preventing the sagging and falling ahead of the sheet as it is being delivered, said means including a 85
85 cross-bar secured to the carrier and adjustable along the same, an arm mounted on said cross-bar and adjustable thereon, a spring 90
90 arm secured to said cross-bar arm and a roller carried by said spring arm.

95 21. A flat sheet delivery mechanism for printing presses including an endless sheet delivery carrier, a stationary sheet support 95
95 and means on the carrier coacting with said support and sheet for preventing the sagging and falling ahead of the sheet as it is being delivered, said means including a cross-bar secured to said carrier, an arm 100
100 laterally and rotatively adjustable on said cross-bar, a spring arm secured to said cross-bar arm and a roller carried by said spring arm.

105 22. A flat sheet delivery mechanism for printing presses including an endless delivery carrier, a stationary sheet support and means on the carrier coacting with said support and sheet for preventing the sagging and falling ahead of the sheet as it is being delivered, said means including a cross-bar 110
110 secured to said carrier, an arm mounted on said cross-bar, a spring arm rotatively adjustable on said cross-bar arm, and a roller carried by said spring arm.

115 23. A flat sheet delivery mechanism for printing presses including an endless delivery carrier, a stationary sheet support, and means on the carrier coacting with said support and sheet for preventing the sagging and falling ahead of the sheet as it is being delivered, said means including a 120
120 cross-bar arm and a roller carried by said spring- 125
125

24. A flat sheet delivery mechanism for printing presses including an endless delivery carrier, a stationary sheet support, means on the carrier coacting with said support and sheet for preventing the sagging and falling ahead of the sheet as it is being delivered, said means including a spring- 130

actuated roller, and means for adjusting the spring tension of said roller.

25. A flat sheet delivery mechanism for printing presses including an endless delivery carrier, a stationary sheet support, and means on the carrier coacting with said support and sheet for preventing the sagging and falling ahead of the sheet as it is

being delivered, said means including a spring-actuated roller and means for adjusting the position of the roller to accommodate it to sheets of different lengths. 10

In testimony, that I claim the foregoing as my invention, I have signed my name this tenth day of September, A. D. 1915.

HOWARD M. BARBER.
